UNITED STATES PATENT OFFICE.

PEARL A. LITTLE, OF FREDERICK, OKLAHOMA.

PUMPING APPARATUS.

1,079,779.

Specification of Letters Patent. Patented Nov. 25, 1913.

Application filed January 23, 1913. Serial No. 743,795.

To all whom it may concern:

Be it known that I, PEARL A. LITTLE, a citizen of the United States, residing at Frederick, in the county of Tillman and State of Oklahoma, have invented new and useful Improvements in Pumping Apparatus, of which the following is a specification.

The present invention has reference to pumping apparatus, and more particularly to that type of apparatus in which the water or other liquid is elevated into a pair of compartments by compressed air or similar motive fluid, such fluid also actuating a controlling mechanism that serves to regulate its supply and exhaust to and from the aforesaid chambers.

The invention resides primarily in certain improvements, hereinafter described at length, in or relating to the above-mentioned controlling mechanism.

An embodiment of the invention is illustrated in the accompanying drawing, of which:

Figure 1 is a vertical sectional view of the improved apparatus; Figs. 2, 3 and 4 are horizontal sections taken, respectively, on the lines 2—2, 3—3, and 4—4 of Fig. 1; Fig. 5 is a vertical section taken on the line 5—5 of Fig. 2; and Fig. 6 is an enlarged inverted, perspective view of one of the parts included in the controlling mechanism.

In said drawing, 1 and 2 indicate, respectively, the left, and right-hand chambers, which are to be alternately filled and emptied; 3 the inlet or supply pipe for the compressed air or other motive fluid; and 4 and 5 the branch pipes through which the liquid is discharged from said chambers, these pipes opening into the main discharge pipe 6.

The chambers 1 and 2 may be of any desired size, and may have any cross-sectional shape considered expedient, and they may be filled in any suitable manner from the main source of liquid supply, the filling being here shown as effected through the agency of inlet openings 7 and 8, having normally-closed one-way valves 9 and 10 associated therewith. At their tops, these chambers, which are depicted as in the form of cylindrical metal tanks, are fitted in seats 11 and 12 in the box 13 that contains the hereinafter-described controlling mechanism. As shown in Fig. 1, this box preferably consists of a pair of superposed plates 14 and 15 which are bolted or otherwise fastened together and are formed with registering openings through which the branch outlet or discharge pipes 4 and 5 project, said pipes extending into the tanks to within a short distance of the bottoms thereof. The upper portions of said pipes are connected by the union 16 with the main discharge pipe 6 and are provided with interiorly-located check valves 17 and 18, these valves being depicted in the present construction as of the ball type, and as supported in seats 19 and 20 formed in the pipes.

The lower plate 14 of the box 13 has formed in its upper face a longitudinal recess 21 which, as will be understood, is covered by the upper plate 15, said recess overlying the tanks 1 and 2 and extending beyond the same at opposite ends. The lower end of the motive-fluid supply pipe 3 opens into this recess, and the latter, in turn, has communication with the tanks 1 and 2 through the openings 22 and 23 and, also, through additional openings subsequently identified and referred to. Thus, it will be seen that the recess constitutes a passageway for the motive-fluid to both tanks. To control the passage of the motive fluid to said tanks, there is provided a slide valve 24, here shown as in the form of a flat block, that is, fitted in recess 21 and is constructed with a longitudinal slot 25 which, during the movements of the valve, is designed to register, alternately, with openings 22 and 23 and is of sufficient length to continuously register with the end of pipe 3. As will be understood from Figs. 1 and 3, said valve moves endwise in its recess, its movements in opposite directions being limited by a pair of blocks 26 and 27 fitted in the ends of said recess. The lower surfaces of these blocks are cut away at their inner ends, as indicated by the numerals 28 and 29, and the said ends themselves are notched as at 30 and 31 and are formed to the rear of said notches with openings 32 and 33 which register with openings 34 and 35 formed through the bottom wall of recess 21. The last-mentioned openings are normally closed by spring-pressed valves 36 and 37 whose stems project therethrough and through the openings 32 and 33. In addition to the various openings already described, there are provided in the plate 14, a pair of openings 40 and 41, which also open into the passageway 21, the upper plate 15 being pro-

vided with a pair of openings 42 and 43 that are located directly above the openings 40 and 41 and are equipped with normally-closed spring-controlled valves 44 and 45. The main valve 24 passes between and thus controls the pairs of openings 40 and 42 and 41 and 43. Finally, there is formed through the bottom wall of recess 21 a pair of openings 46 and 47, which are located beneath the notches 30 and 31 and have fitted in their enlarged lower portions the upper ends of a pair of depending sleeves 48 and 49, said sleeves being provided, in turn with ports 50 and 51. These ports are located in the upper portions of the sleeves and are covered and uncovered by a pair of vertical rods 52 and 53 carrying floats and 55 at their lower ends.

Assuming that the parts are in the positions shown in Fig. 1, with the tank 1 filling and the tank 2 emptying, the operation may be briefly described as follows: The motive fluid admitted through pipe 3 flows through slot 25 in the slide valve 24 and thence through opening 23 into tank 2, where it forces the liquid contained therein to rise through branch pipe 5 into union 16 and finally into and through discharge pipe 6, the liquid raising the check valve 18 from its seat 20 during its passage through said branch pipe. Throughout this operation, the inlet valve 10 remains closed, but opens when the tank has emptied, at which time, the float 55 drops to such an extent that the end of its rod 53 uncovers port 51. The motive fluid, which still continues to flow into tank 2, will then enter sleeve 49 through said port 51 and will enter the passage-way 21 by way of opening 47, the latter leading to the space 29 beneath the inner end of block 27. Opening 47, as above stated, is disposed beneath the notch 31 in said block, and hence the motive fluid, on entering the passageway, will exert its force against the main slide valve 24 and will shift the latter to the left until it strikes against block 26. This movement serves to bring the valve slot 25 into registration with opening 22, and, at the same time, to uncover opening 41 and cover opening 40, thereby causing the motive fluid to enter tank 1 by way of said opening 22, any motive fluid, or liquid, which may be contained in said passageway in front of said valve, being forced therefrom into tank 1 through the valve-controlled opening 34. As the tank 2 empties, the tank 1 gradually fills, so that when valve 24 is actuated, as above described, the latter tank is full, the tank 2 being re-filled by the time that tank 1 is again empty. During the filling operation, assuming, for example, that such operation is taking place in tank 1, the motive fluid contained in said tank above the in-coming liquid is forced out through the opening 40 into the passage-

way 21, and escapes from the latter to the atmosphere through the valve-controlled openings 42.

The apparatus, with but little change, may be used with equal facility for pumping water either for ordinary purposes or for fire-fighting, and for draining and similar operations connected with sewerage.

What is claimed is:

1. In a pumping apparatus, the combination, with a pair of chambers having inlet openings for the liquid to be pumped, and a discharge pipe in communication with both chambers; of a box wherein the upper ends of said chamber are fitted, having a motive fluid inlet opening in communication with each chamber; a motive fluid supply pipe leading into said box; and controlling mechanism arranged in said box for supplying the motive fluid to said chambers alternately, comprising a reciprocatory slide valve having a longitudinal slot which is in constant communication with the outlet end of said supply pipe and in alternate communication with said motive fluid inlet openings during its movements, and a pair of float-controlled valves for automatically delivering the motive fluid from either chamber behind the adjacent end of said slide valve to shift the latter toward the other chamber when the contents of the first-mentioned chamber are exhausted.

2. In a pumping apparatus, the combination, with a pair of chambers having inlet openings for the liquid to be pumped, and a discharge pipe in communication with both chambers; of a box wherein the upper ends of said chambers are fitted having a motive-fluid inlet opening in communication with each chamber; a motive fluid supply pipe leading into said box; and controlling mechanism arranged in said box for supplying the motive fluid to said chambers alternately, comprising a reciprocatory slide valve having a longitudinal slot which is in constant communication with the outlet end of said supply pipe and in alternate communication with said motive fluid inlet openings during its movements, a pair of open-ended sleeves secured to said box behind the ends of the slide valve and projecting into said chambers, each sleeve being provided adjacent its upper end with an inlet port, and a float arranged in each chamber and having its stem extending upwardly into the corresponding sleeve to normally close the port therein, whereby the fall of either float consequent upon the emptying of the corresponding chamber will cause its stem to uncover the port in the corresponding sleeve, and permit the motive fluid in that chamber to pass into said box behind the adjacent end of said slide valve, to shift the latter toward the other chamber.

3. In a pumping apparatus, the combina-

tion, with a pair of chambers having inlet openings for the liquid to be pumped, and a discharge pipe in communication with both chambers; of a box wherein the upper 5 ends of said chambers are fitted provided with a longitudinal passage-way having motive-fluid inlet openings formed through its bottom wall communicating with said chambers; a motive fluid supply pipe opening 10 through the top wall of said passage-way; a slide valve slidable in opposite directions in said passage-way and provided with a longitudinal slot, which is in continuous communication with the outlet end of said 15 supply pipe during the movements of the valve and which communicates alternately with said motive-fluid inlet openings; a stop block fitted in each end of said passage-way for limiting the movements of 20 said slide valve, each block having a notched and undercut inner end; a pair of open-ended depending sleeves secured to the bottom wall of said passage-way directly beneath the aforesaid ends of said stop blocks, 25 each sleeve being provided adjacent its upper end with an inlet port; and a float arranged in each chamber and having its stem extending upwardly into the corresponding sleeve to normally close the port therein, whereby the fall of either float consequent 30 upon the emptying of the corresponding chamber will cause its stem to uncover the port in the corresponding sleeve, and permit the motive fluid in that chamber to pass into said box behind the adjacent end of 35 said slide valve, to shift the latter toward the other stop block.

4. In a pumping apparatus, the combination, with a pair of chambers having inlet openings for the liquid to be pumped, and a discharge pipe in communication with both chambers; of a box wherein the upper 40 ends of said chambers are fitted provided with a longitudinal passage-way having motive-fluid inlet openings formed through its bottom wall communicating with said chambers; a motive fluid supply pipe opening 45 through the top wall of said passage-way; a slide valve slidable in opposite directions in said passage-way and provided with a longitudinal slot, which is in continuous communication with the outlet end of said supply pipe during the movements of the valve and which communicates alternately with said motive-fluid inlet openings; a stop block fitted in each end of said passage-way for limiting the movements of 50 said slide valve, each block having a notched and undercut inner end; a pair of open-ended depending sleeves secured to the bottom wall of said passage-way directly beneath the aforesaid ends of said stop blocks, each sleeve being provided adjacent its upper end with an inlet port; and a float arranged in each chamber and having its stem extending upwardly into the corresponding sleeve to normally close the port therein, whereby the fall of either float consequent 55 upon the emptying of the corresponding chamber will cause its stem to uncover the port in the corresponding sleeve, and permit the motive fluid in that chamber to pass into said box behind the adjacent end of 60 said slide valve, to shift the latter toward the other stop block.

5. In a pumping apparatus, the combination, with a pair of chambers having inlet openings for the liquid to be pumped, and a discharge pipe in communication with both chambers; of a box wherein the upper 65 ends of said chambers are fitted provided with a longitudinal passage-way having motive-fluid inlet openings formed through its bottom wall communicating with said chambers; a motive fluid supply pipe opening

In testimony whereof I have hereunto set my hand in presence of two subscribing witnesses.
